UNITED STATES PATENT OFFICE.

LIONEL MANUEL HENDLER, OF BALTIMORE, MARYLAND.

CONTAINER FOR ICE-CREAM BLOCKS.

1,246,265.

Specification of Letters Patent. Patented Nov. 13, 1917.

Application filed April 6, 1916. Serial No. 89,384.

To all whom it may concern:

Be it known that I, LIONEL MANUEL HENDLER, a citizen of the United States, residing at Baltimore, in the State of Maryland, have invented certain new and useful Improvements in Containers for Ice-Cream Blocks, of which the following is a specification.

This invention relates to packing and storing vessels, and particularly to receptacles adapted to contain blocks or bricks of ice cream, or the like, and to preserve the same in a frozen condition.

In the commercial handling of frozen products, such as ice cream, it is the practice to first freeze the cream to a stiff, plastic condition and then to mold or cut it into suitable blocks or bricks. These blocks are usually inclosed in paper cartons, or other suitable wrappers, and are then packed in a container which is itself placed in a receptacle containing a refrigerating mixture. This subjects the blocks to further freezing and maintains them in proper condition for serving.

The containers heretofore employed for packing the blocks have usually been of rectangular shape, and of a width and length approximately equal to the corresponding dimensions of the blocks to be packed, or multiples thereof.

It has also been the practice in some cases to employ round containers, in which the blocks are placed on end instead of horizontally, but in such containers there is considerable loss of space, and moreover, the blocks are apt to become crushed and damaged by their own weight because of the fact that they are not laterally confined.

It is the object of the present invention to provide a container for holding ice cream blocks of this character which shall avoid the defects and difficulties heretofore experienced. To this end, the invention contemplates the provision of a container, one horizontal dimension of which is substantially equal to the corresponding dimension of the blocks, so that two of the vertical faces of the blocks will be in contact with the walls of the container, while the other horizontal dimension is greater than the corresponding dimension of the blocks, whereby a space is provided between the other two vertical faces of the blocks and the adjacent walls of the container. By this means, the blocks are firmly held in hori-

zontal position in a compact mass or stack and are subjected to the freezing action of the refrigerating mixture, while, at the same time, they may be readily grasped between the fingers and easily removed from the container.

In order that the invention may be readily understood, reference is had to the accompanying drawings, in which,

Figure 1 is a vertical, central section through one of my improved containers, showing the blocks in elevation, and the container disposed within the outer receptacle containing the refrigerating mixture;

Fig. 2 is a perspective view of the preferred form of the container itself;

Fig. 3 is a plan view of the parts shown in Fig. 1; and,

Figs. 4 and 5 are plan views showing slightly modified forms of container.

Referring to the drawings in detail, the outer receptacle or tub is designated by the numeral 1, and the container by the numeral 2. The tub may be of wood, as usual, while the container is preferably formed of sheet metal, and is provided with a removable cover 2a.

By reference to Fig. 2, it will be seen that the container comprises flat end walls 3, which are separated a distance equal to the length of the blocks or bricks indicated at A, and of a width substantially equal to the width of said blocks. The side walls 4 of the container, however, are spread apart so that the width of the container between these walls is greater than the width of the blocks A, and a space Y is provided between the sides of the blocks and the walls 4, as clearly shown in Fig. 3. This space, it will be seen, permits of the topmost block being readily grasped between the fingers of the operator and easily lifted from the container, while, at the same time, the end faces of the blocks are in direct contact with the flat walls 3 of the container, and are thus subjected to the freezing action of the refrigerating mixture. This refrigerating mixture usually consists of ice and salt and is packed in the space X, between the container and the tub 1, in the usual manner.

In order to properly center the container in the tub, and insure the uniform distribution of the refrigerating mixture therearound, I provide brackets 5, attached to the end walls 3 of the container and adapted to engage the inside of the tub, as shown in

Fig. 3. These brackets may be located at any point in the height of the container, but it is found more convenient to place them at the bottom, as illustrated in Fig. 2.

5 Instead of the curved walls 4, as shown in Figs. 2 and 3, I may form each side of the receptacle of a pair of straight, diverging walls 6, as shown in Fig. 4. In this case, a pocket or space Y' is formed between such 10 walls and the blocks, the same as in Fig. 3.

Instead of constructing the angularly disposed side walls to extend directly from the end walls, as in Fig. 4, I may arrange them as indicated at 8, in Fig. 5. In this case, 15 parallel side walls 7 are provided at each end of the container and the angularly disposed walls 8 are located only adjacent the center thereof. These walls 8 form pockets 20 Y², which are smaller than the spaces or pockets Y or Y', with the result that a greater part of the faces of the block are in direct contact with the container walls, and the refrigerating action on the blocks is therefore greater.

25 In all of the forms of container shown in the drawings, therefore, it will be seen that the blocks are securely maintained in horizontal position and in superposed relation with at least two faces in direct contact with the walls of the container and exposed to the chilling action of the refrigerat-

ing mixture, while, at the same time, there is a free space adjacent two faces of the blocks so that they may be readily grasped and easily removed from the container.

While I have shown and described my improved container as being particularly applicable to packing ice cream blocks, it will, of course, be understood that it also has utility in connection with the packing of other blocks or packages of such a nature that difficulty is experienced in removing them from the container.

What I claim is:

The combination with an outer receptacle 45 adapted to receive a refrigerating mixture, of an inner container for ice cream blocks disposed in said receptacle, one dimension of said container being equal to that of the blocks, whereby two faces of the blocks are 50 in contact with the walls of said container, and subjected to the action of the refrigerating mixture, and the other dimension of said container being greater than that of the blocks, whereby a free and unobstructed 55 space is provided between two other faces of the blocks and the adjacent walls of the container.

In testimony whereof I have affixed my signature.

LIONEL MANUEL HENDLER.
